[57] **CLAIM**

The ornamental design for a topical applicator with cap, as shown and described.

DESCRIPTION

FIG. 1 is a front view of the cap portion of the topical applicator, showing my new design;

FIG. 2 is a right side view thereof;

FIG. 3 is a top, rear perspective view thereof;

FIG. 4 is a bottom, front perspective view thereof;

FIG. 5 is a top plan view thereof;

FIG. 6 is a bottom, rear perspective view thereof;

FIG. 7 is a top plan view of the topical applicator with cap attached;

FIG. 8 is a rear view thereof;

FIG. 9 is a left side view thereof;

FIG. 10 is a front view thereof;

FIG. 11 is a top perspective view thereof; and,

FIG. 12 is a bottom perspective view thereof.

The surface(s) or portion(s) of the article not shown in the drawing or described in the specification form(s) no part of the claimed design.
